United States Patent Office

Des. 210,454
Patented Mar. 12, 1968

210,454

SOFA OR SIMILAR ARTICLE

Vladimir Kagan, 1225 Park Ave.,
New York, N.Y. 10028

Filed Mar. 10, 1967, Ser. No. 6,150

Term of patent 7 years

(Cl. D15—11)

FIG. 1

FIG. 2

FIG. 3

FIG. 1 is a top front perspective view of a sofa or similar article, showing my new design;

FIG. 2 is a front elevational view thereof; and

FIG. 3 is an end view thereof.

A rear elevational view of the sofa is the same as the FIGURE 2 showing while the end not shown is a mirror image of the end shown.

I claim:

The ornamental design for a sofa or similar article, substantially as shown and described.
